TRIGGER FOR MACHINE GUNS

John L. Lochhead, Springfield, Mass.

Application March 2, 1938, Serial No. 193,533

8 Claims. (Cl. 42—69)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a trigger for machine guns.

The Browning machine gun as shown in Patent No. 2,050,538 of August 11, 1936, is provided with a trigger in the form of a simple lever which 10 provides for automatic firing so long as it is held in the firing position. Firing is interrupted only by releasing the trigger, but due to rapid action of the gun it is impossible to control single-shot firing.

15 The purpose of this invention is to provide a trigger mechanism which is simple and inexpensive, which may be readily installed to replace the present Browning trigger without modifying its normal action, and which in operation maintains 20 the throw, pull and all characteristics of the present trigger.

These purposes are accomplished by providing a trigger mechanism in the form of a compound lever which includes a link normally connecting 25 elements of the mechanism and arranged to be disconnected therefrom by the reciprocating breech bolt of the gun.

To these and other ends, the invention consists in the construction, arrangement and combination of elements described hereinafter and pointed out in the claims forming a part of this specification.

A practical embodiment of the invention is illustrated in the accompanying drawing, where- 35 in:

Fig. 1 is a view partly in side elevation and partly in section of the rear portion of a Browning gun showing the trigger mechanism in the neutral position;

40 Fig. 2 is a view in rear elevation;
Fig. 3 is a plan view;

Figs. 4, 5 and 6 are detail views in side elevation showing the parts respectively in neutral, fired and disconnected positions when the mechanism 45 is arranged for semi-automatic firing;

Fig. 7 is a view showing the adjustment for automatic firing.

Referring to the drawing by characters of reference there is shown a portion of a machine gun of the Browning type including a receiver A having a back plate B, handle C, and a reciprocating breech bolt D which carries a sear E engageable with the firing pin F and actuated by a trigger bar G pivotally mounted in the receiver.

50 The improved trigger mechanism is carried

by the back plate B in the same manner as the conventional trigger. It consists generally of a hand trigger 5, a trigger lever 6 for engaging the bar G, and a link 7 for connecting the trigger and lever. The trigger 5 to which is fixed a finger piece 8 has a bifurcated front end 9 which is disposed in a slot 10 in the back plate and is rotatably mounted on a pin 11 carried by the back plate and extending transversely of the slot. The under side of each division of the 10 bifurcated end 9 is notched to provide a projecting finger 12.

The lever 6 is rotatably mounted on the pin 11 within the bifurcated end 9 and includes a rearwardly extending arm 13 and a downwardly 15 extending arm 14 of greater width than the arm 13 and adapted to engage the bar G. The arm 14 is normally held away from the bar G and against the inner side of the back plate by means of a helical spring 15 confined between said arm 20 and the top plate of the receiver.

The link 7 which is rotatably mounted on a pin 16 carried by the arm 13 of the lever 6 includes a downwardly extending arm 17 positioned in rear of the back plate and spaced arms 18 extending forwardly into the slot 10 and underneath the front end 9 of the trigger. Each arm 18 terminates in a finger 19 which is adapted to be normally disposed in front of the corresponding finger 12 of the trigger when the rear portions of the trigger and link are separated by a helical spring 20. This engagement of the fingers limits separation of the trigger and link under the influence of the spring and establishes a driving connection between them when pressure is applied to the trigger to depress it.

The arm 17 of the link carries a housing 21 whose front portion is provided with a diametral slot 22 and is arranged to move through an aperture 23 in the back plate. A rod 24 passing through the housing and arm has a head 25 on its front end which is adapted to one position of adjustment (Figs. 4-6) to engage the front face of the housing and serve to increase the effective 40 length of the rod and in another position of adjustment (Fig. 7) which is established by rotating it through ninety degrees to be received in the slot 22 of the housing. A thumb nut 26 is threaded on the rear end of the rod 24 and a 45 spring 27 embracing the rod and confined between the thumb nut and the rear face of the arm 17 of the link, serves to hold the rod in position of adjustment.

In Figs. 1 and 4 the trigger mechanism is shown 55

in the neutral or unfired position, the head 25 on the rod 24 being adjusted to provide for semi-automatic firing. When pressure is applied to the finger piece 8 the trigger 5 is depressed and 5 by virtue of the engagement of the fingers 12 and 19 the link 7 connects the trigger 5 and lever 6 and these members are rotated as a unit about the pin 11 as shown in Fig. 5.

In this firing position the lever 6 trips the bar 10 G which depresses the sear E and fires the gun. The head 25 carried by the link has been moved 15 through the back plate and is now disposed in the path of movement of the reciprocating breech bolt D.

15 Upon firing of the gun the breech bolt is moved rearwardly and at the end of its recoil stroke it strikes the head 25 and swings the link about its pivot pin 16 to disconnect it from the trigger 5 by moving the fingers 19 below and out of the 20 path of the fingers 12 of the trigger. As soon as the fingers are disengaged, the spring 15 which is stronger than the spring 20 restores the lever 6 to 25 neutral position and in so doing the pin 16 carried by the lever 6 moves about the pin 11 as a center and is thereby displaced sufficiently to the rear so that the upper surfaces of the fingers 19 will engage the lower surfaces of the fingers 12 as 30 shown in Fig. 6. So long as pressure is exerted on the trigger to hold it in depressed position this 35 relationship of the fingers will be maintained and the spring 20 will remain compressed. The lever 6 no longer exerts pressure on the bar G so that when the breech bolt returns into battery the sear E will not be actuated to release the firing pin F from cocked position.

In order to reestablish an operative relationship of the parts it is necessary to relieve pressure on the trigger 5 whereupon the spring 29 acts to separate the rear ends of the trigger and 40 link and enable the fingers 12 of the trigger to reengage the fingers 19 of the link. The parts are now in the position shown in Fig. 4 and in order to fire the next shot the trigger must be depressed.

45 When it is desired to fire automatically the rod 24 is partially rotated to align the head 25 and the slot 22 and enable the spring 27 to retract the rod, the head entering the slot. In this position of adjustment of the parts the head 25 will not 50 be struck by the breech bolt D when the mechanism is moved as a unit into firing position.

A spring 28 is carried by a portion of the back plate and engages the finger piece 8 to normally hold it in safe or unfired position.

55 I claim:

1. In a machine gun, a receiver having a back plate with a slot and an aperture, a reciprocal breech bolt in the receiver, a sear in the breech bolt, a trigger bar for operating the sear, a pin in 60 the back plate transversely of the slot therein, a trigger having a bifurcated front end pivotally mounted on the pin, each division of said front end having a projecting finger on its lower side, a lever pivotally mounted on the pin within the bifurcated end of the trigger, said lever including 65 a depending arm adapted to actuate the trigger bar, a spring acting on the lever to hold the arm away from the trigger bar and against the back plate, a link pivotally mounted on the lever and 70 having spaced arms each with a finger engageable with the correspondingly positioned finger of the trigger, a spring between the trigger and link and normally maintaining them connected through their fingers, a depending arm on the link, and means adjustable for length carried by 75

the link and movable through the aperture in the back plate, said means in one position of adjustment engageable by the breech bolt to disconnect the link from the trigger.

2. In a machine gun, a receiver having a back plate, a reciprocal breech bolt in the receiver, a sear in the breech bolt, a trigger bar for operating the sear, a pin in the back plate, a trigger pivotally mounted on the pin and including a projecting finger, a lever pivotally mounted on the pin and including an arm adapted to actuate the trigger bar, a spring acting on the lever to hold the arm away from the trigger bar and against the back plate, a link pivotally mounted on the lever and including an arm with a finger engageable with the finger of the trigger, a spring between the trigger and link and normally maintaining them connected through their fingers, a depending arm on the link, and means adjustable for length carried by the link and movable through the back plate, said means in one position of adjustment engageable by the breech bolt to disconnect the link from the trigger. 15

3. In a machine gun, a receiver having a back plate, a reciprocal breech bolt in the receiver, a sear in the breech bolt, a trigger bar for operating the sear, a pin in the back plate, a trigger pivotally mounted on the pin and including a projecting finger, a lever pivotally mounted on the pin and including an arm adapted to actuate the trigger bar, a spring acting on the lever to hold the arm away from the trigger bar and against the back plate, a link pivotally mounted on the lever and including an arm with a finger engageable with the finger of the trigger, a spring between the trigger and link and normally maintaining them connected through their fingers, and means whereby the link is engageable by the breech bolt to disconnect it from the trigger. 30

4. In a machine gun, a receiver having a back plate, a reciprocal breech bolt in the receiver, a sear in the breech bolt, a trigger bar for operating the sear, a pin in the back plate and including a projecting finger, a lever pivotally mounted on the back plate and adapted to actuate the trigger bar, a spring acting on the lever to hold it away from the trigger bar, a link pivotally mounted on the lever and including a projecting finger engageable with the finger of the trigger, a spring between the trigger and link and normally maintaining them connected through their fingers, and means carried by the link and positionable to be engaged by the breech bolt to disconnect the link from the trigger. 45

5. In a machine gun, a receiver, a reciprocal breech bolt in the receiver, a trigger bar mounted on the receiver, a trigger pivotally mounted on the receiver, a lever pivotally mounted on the receiver and adapted to actuate the trigger bar, a spring for normally holding the lever away from the trigger bar, a link pivotally mounted on the lever and connectable and disconnectable with the trigger, a spring between the trigger and link and normally maintaining them connected, and means carried by the link and positionable to be engaged by the breech bolt to disconnect the link from the trigger. 60

6. In a machine gun, a receiver, a reciprocal breech bolt in the receiver, a trigger bar mounted on the receiver, a trigger pivotally mounted on the receiver, a lever pivotally mounted on the receiver and adapted to actuate the trigger bar, a link carried by the lever and normally coupling 70

the trigger and lever whereby they are movable as a unit, said link arranged to be engaged by the breech bolt to uncouple the trigger and lever.

7. In a machine gun, a receiver, a reciprocal breech bolt in the receiver, a trigger bar mounted on the receiver, a trigger pivotally mounted on the receiver, a lever pivotally mounted on the receiver and adapted to actuate the trigger bar, and means normally coupling the trigger and lever whereby they are movable as a unit, said means adjustable to be selectively clear of and engageable by the breech bolt and when engaged

by the breech bolt to uncouple the trigger and lever.

8. In a machine gun, a receiver, a reciprocal breech bolt in the receiver, a trigger bar mounted on the receiver, a trigger pivotally mounted on the receiver, a lever pivotally mounted on the receiver and adapted to actuate the trigger bar, and means normally coupling the trigger and lever whereby they are movable as a unit, said means engageable by the breech bolt to uncouple the trigger and lever. 5 10
